UNITED STATES PATENT OFFICE.

MICHAEL C. CARUOLO, OF THORNTON, RHODE ISLAND.

SAFETY MECHANISM.

1,199,875.

Specification of Letters Patent.

Patented Oct. 3, 1916.

Application filed April 26, 1916. Serial No. 93,632.

To all whom it may concern:

Be it known that I, MICHAEL C. CARUOLO, a citizen of the United States, residing at Thornton, in the county of Providence and State of Rhode Island, have invented certain new and useful Improvements in Safety Mechanisms, of which the following is a specification.

My invention relates to a safety mechanism adapted in case of collision, to automatically prevent the advance of the vehicle to which the mechanism is attached.

The essential objects of my invention are to check the momentum of the vehicle in its advance in case of a collision; to reverse the direction of travel of the same at the instant of collision; to prevent excessive travel in the reversed condition; and to attain these ends in a structure which is simple to construct and operate, and adapted for facile removal for the substitution of tires.

To the above ends essentially my invention consists in such parts and combinations of parts as fall within the scope of the appended claims.

In the accompanying drawings which form a part of this specification, Figure 1 is a side elevation of the chassis or lower body portion of a vehicle equipped with my novel mechanism, Fig. 2, a bottom plan of the mechanism, omitting the vehicle body except the tubes, Fig. 3, an elevation similar to Fig. 1, but showing the device in depressed position.

Like reference characters indicate like parts throughout the views.

In the drawings A represents the chassis or body of an automobile or other vehicle, carrying the usual front and rear axles B and C, with their respective wheels b and c. Fixed to the bottom of the chassis or vehicle body, at each side of the center thereof, are longitudinally disposed tubes or sleeves D provided near their rear ends with longitudinal slots d. Slidably mounted in the sleeves are the side bars e of a frame E having a forward end rod f, and, in the present instance, a rear end rod g. The length of the frame E is in excess of the length of the body of the vehicle, so that the forward end portion of the former projects some distance in front of the latter. Fixed to portion f of the frame by sleeves h or otherwise is a vertical screen or buffer member H of rectangular or other shape.

The described frame operates, through

suitable connections, guard frames pivotally attached to each end of the rear axle C, and as these frames and connections are of similar construction, a description of one set will serve for both. Each frame I comprises parallel open side plates i of a generally triangular shape. The upper portion of each plate is a substantially straight strip or rod j, and the lower portion consists of downwardly converging strips or rods j² and j³, having their intermediate portions upwardly curved, and the portions j² being longer than the portion or leg j³. The side plates are joined by one or more transverse plates or bars K. In the front apices of the plates i are pins l on which are mounted rollers L. In the rear apices of the plates at the points of intersection of the portions j² and j³ are transverse pins m on which are mounted rollers or wheels M. The rearmost apices of the plates i are provided with open bearings or openings n adapted to receive the axle C, and closed by locking latches N pivoted at o, by which construction the frame I may be removed, when desired, from the axle. The bearings n have sufficient play to allow the wheels c to move into or out of contact with the rollers M. Since the plates i are located on each side of both wheels c this disengaging means is convenient when it is desired to substitute a tire.

In an intermediate portion of both the inner plates i is a pin p which is pivotally connected with the lower end of a rod P whose upper end is pivoted to a pivot pin q carried by a lug s on the frame bar e. The reciprocation, therefore, of the frame E serves, through the rods P, to simultaneously elevate and lower the forward portions of the frames I which oscillate on the rear axle.

The operation of my devise is as follows: The vehicle advances with the parts in the positions shown in Figs. 1 and 2. The frames I are positioned horizontally with the rollers elevated above the ground. The concave character of portions j² and j³ of the frames protect the same from road obstructions, not only by reason of increasing their elevation but by their inclined form. The forward projection of the frame E serves to bring the member H into contact with any obstruction. This contact immediately forces the frame E rearwardly relatively to the vehicle, and as shown in Fig. 3, the rods P downwardly oscillate the

2
frames I and bring the rollers into contact with the ground. The length of the portions j^2 of the frames is in excess of the radius of the wheels c including the tires, so that immediately the rollers engage the ground the forward momentum of the vehicle co-operates to raise the wheels from the ground into contact with the rollers M which are thereby rotated so that the machine is moved rearwardly, the end g of the frame E being at this instant projecting to the rear of the vehicle. If at this instant the portion g contact with some obstruction the frames I are forced upwardly and the wheels return to the ground where they operate with much diminished speed forwardly. Thus the vehicle is either stopped without any rearward travel whatever in case of less violent collisions; and in case of more violent collision, moves rearwardly; and in some cases, may vibrate first rearwardly and then forwardly.

It will be understood that auxiliary manually operative means may be employed if desired to reciprocate the horizontal frame E, but such means it will be understood are strictly auxiliary to the means herein shown.

I claim:—

1. The combination with the body, axle, and wheels of a vehicle, of vibratory guard frames pivotally mounted on the axle adjacent the wheels, and of greater length than the radius of the wheels, rollers on the guard frames, and means on the body operable by the momentum of the body for vibrating the guard frames whereby the wheels are elevated from the ground and brought into operative engagement with the rollers.

2. The combination with the body, axle, and wheels of a vehicle, of a frame slidably mounted on the body and projecting forwardly thereof, guard frames pivotally mounted on the axle adjacent the wheels and projecting forwardly thereof, rollers on the projecting portions of the guide frames, and rods pivotally connecting the first frame with the guard frames whereby the wheels are elevated from the ground and brought into operative engagement with the rollers.

3. The combination with the body, axle, and wheels of a vehicle, of vibratory guard frames pivotally mounted on the axle inside thereof, rollers upon the frames, and slideable means on the body operable by the momentum of the body for vibrating the frames whereby the wheels are elevated from the ground and brought into operative engagement with the rollers.

4. The combination with the body, axle, and wheels of a vehicle, of a frame slidably mounted on the body and extending forwardly thereof, guard frames pivotally mounted on the axle adjacent the wheels 65 and extending forwardly thereof, rollers on the guard frames disposed angularly with relation to the axle, and pivotal connections between the first frame and the guard frames whereby the wheels are elevated from 70 the ground and brought into operative engagement with the rollers.

5. The combination with the body, axle and wheels of a vehicle, of vibratory guard frames surrounding the wheels and provided at their rear portions with open bearings adapted to receive the axles, latches on the frames closing the bearings, rollers on the frames, and slidable means on the body operatively connected with the frames 80 for actuating the frames whereby the wheels are elevated from the ground and brought into operative engagement with the rollers.

6. The combination with the body, axle, and wheels of a vehicle, of a horizontal 85 frame slidably mounted in the body and projecting forwardly thereof, a guard upon the forward end of the frame, guard frames pivotally mounted on the axles and extending forwardly thereof, rollers on the guard 90 frames, and rods pivotally connecting the first frame with the guard frames whereby the wheels are elevated from the ground and brought into operative engagement with the rollers.

7. The combination with the body, axle, and wheels of a vehicle, of a horizontal frame slidably mounted on the body and of greater length than the body, triangular guard frames pivotally mounted at one corner to the axle and having their other two corners extending forwardly of the wheels, rollers in the said two corners, and pivotal members connecting the first frame with the guard frame whereby the wheels are elevated from the ground and brought into operative engagement with the rollers.

8. The combination with the body, axle, and wheels of a vehicle, of vibratory guard frames pivotally mounted on the axle adjacent the wheels, rollers on guard frames, a horizontal frame slidably mounted in the body, and rods pivotally connecting the horizontal frame with the guard frames whereby the wheels are elevated from the ground and brought into operative engagement with the rollers.

In testimony whereof I have affixed my signature.

MICHAEL C. CARUOLO.
